COATING MACHINE

James H. Gordon, Jr., Geneva, N. Y., and Victor T. Grover, Maplewood, N. J., assignors to American Can Company, New York, N. Y., a corporation of New Jersey

Application June 10, 1941, Serial No. 397,486

8 Claims. (Cl. 91—55)

The present invention relates to that class of coating machines in which the articles to be coated are dipped into the coating material and then are allowed to drain and has particular reference to timing the draining period to control the quantity of coating material which remains on the article and to indicate over-drained or thinly coated articles so that they may be discarded.

In the manufacture of certain kinds of containers, such as for example, those made of fibre material and the like, the containers are immersed into a bath of coating material and then allowed to drain for a predetermined period of time in accordance with the viscosity of the material so that a film of a desired thickness of the coating material will remain on the container after such drainage period. Where these coating and draining operations are performed by high speed machinery, frequent stops in the travel of the containers through the machines are sometimes experienced because of container jams or the stopping and starting of other machines used in conjunction with the coating machines.

When the coating machine stops, even momentarily, the containers being drained may remain in the draining section of the machine for a longer period than required. Hence a greater quantity of the coating material will be drained off of these containers and the resultant film on the containers will be of a reduced thickness. Such thinning of the coating film on a container is often intolerable where high standards of quality are involved and thus such a container being below standard is rendered useless.

The instant invention contemplates the sorting out of such over-drained containers and the marking or otherwise designating of them so that upon inspection they may be readily detected and discarded to the end that they will be prevented from entering the regular channels incident to commercial use.

An object therefore of the invention is the provision in a coating machine of the character in which articles are dipped and drained, of devices wherein overdrained articles are singled out and specially indicated as such so that they may be readily detected and discarded to prevent their further use as commercial articles.

Another object is the provision in such a machine, of devices which begin to operate only at the termination of operation of the machine so that articles remaining in the draining section of the machine in excess of a predetermined period are indicated as over-drained articles so that they will be discarded.

Another object is the provision in a machine of this character, of devices which accumulate short delays in the progress of an article through the

draining section of the machine and register the article as over-drained when the accumulated delays equal or exceed a predetermined amount in a required period of time so that such registered articles may be discarded from use.

Numerous other objects and advantages of the invention will be apparent as it is better understood from the following description, which, taken in connection with the accompanying drawings, discloses a preferred embodiment thereof.

Referring to the drawings:

Figure 1 is a top plan view of a coating machine embodying the instant invention, with parts broken away and other parts shown in section;

Fig. 2 is a vertical sectional view taken substantially along the line 2—2 in Fig. 1, with parts broken away;

Fig. 3 is a view similar to Fig. 2 showing a continuation toward the left of the apparatus illustrated in that figure;

Figs. 4, 5 and 6 are transverse vertical sectional views taken substantially along the respective lines 4—4, 5—5, 6—6 in Fig. 3 and showing the draining of a container, with parts broken away; and

Fig. 7 is an enlarged perspective schematic view showing principal mechanical and electrical parts of the machine with an overdrained coated article in place, the view including a wiring diagram of the electric apparatus used in the machine.

As a preferred embodiment of the invention, the drawings illustrate principal parts of a coating machine for applying a film of coating material of a predetermined thickness onto fibre milk containers A (Fig. 7) of the character disclosed in United States Patent 2,085,979, issued July 6, 1937, to J. M. Hothersall.

Such a container is preferably of square cross-section and is provided in its top end with a dispensing opening adapted after filling to be closed with a hingedly attached closure element B. The entire inside and outside surfaces of the container are preferably coated with molten paraffin wax.

In the machine the containers A enter in a horizontal position by way of a curved runway 11 (Fig. 2). The containers are propelled along this runway in spaced and timed order by a rotating star wheel 12 which may be revolved in any suitable manner. Adjacent the terminal end of the runway, the entering containers A are picked up by an endless chain coating conveyor 13 having pockets in cradles 14 in which the containers are received.

The conveyor 13 operates over spaced sprockets 16 located adjacent the ends of the machine. The containers are carried along the lower run of the

conveyor and guide rails 17, disposed adjacent the path of travel of this run, confine the containers in the cradle pockets. The containers enter the machine with their closure elements B in an open condition and they are maintained in this condition by a guide rail 18 against which they engage and along which they slide.

The lower run of the conveyor 13 carries the containers down into a bath of the molten paraffin wax contained in a reservoir 21 disposed adjacent the conveyor. In passing through this bath the containers are completely submerged and the closure element is still held open so that the liquid wax will flow into the container filling the same and completely covering its inside surfaces as well as the outside.

At the far end of the reservoir 21 the conveyor carries the containers up out of the wax bath and over the sprocket 16 at that end of the machine so that the wax filled containers will be on the top run of the conveyor. The guide rails 17 and closure element rail 18 extend parallel with the conveyor to maintain the containers properly in the conveyor pockets.

In moving along the upper run of the conveyor 13, the containers are first tilted endwise into an inverted position as shown in Figs. 4, 5 and 6, so that all the excess wax within the containers will drain out. Farther along the conveyor, the containers are tilted back through their horizontal position into an upright position with their open closure elements up, as shown in Fig. 1. This tilting of the containers may be effected in any suitable manner such as by a twisting of the guide rails.

At the termination of the upper run of the conveyor 13 the coated and drained containers are picked up by a turret 25 (Fig. 1) which rotates in time with the coating conveyor. This turret carries the containers through a curved path of travel and transfers them into an auxiliary or cooling conveyor 26 which operates over a pair of spaced horizontal sprockets 27, only one of which is illustrated in Fig. 1.

The sprockets 27 are located adjacent the opposite ends of the machine and are rotated in any suitable manner in time with the turret 25 and coating conveyor 13. This auxiliary conveyor carries the containers through a cooling section 28 of the machine in which the applied coating on the containers is set hard.

The conveyor is operated at a predetermined speed which is based on the viscosity of the liquid wax, so that the time it takes a container to traverse the length of the upper run of the conveyor, such will be the correct time required to properly drain the container. This predetermined period is calculated to leave a film of wax of a desired thickness on the surfaces of the container.

As long as the machine remains in full operation the timing of the draining period will be correct and will be maintained. However, if the machine stops or momentarily ceases operation, a timing mechanism is set in motion to time the passage of the containers along the conveyor 13.

In the present case by way of example, the normal draining period of the containers is thirty seconds and a leeway of ten seconds more is figured as being permissible before they will be considered as over-drained containers. Thus if the machine stops for a ten second period in thirty seconds, certain of the containers on the conveyor will be over-drained and such should be marked for discarding. If the machine stops only momentarily, the time periods consumed by these

momentary stops are added together and if in any thirty second period the accumulated stops amount to as much as ten seconds, certain of the containers will be considered over-drained and these also should be marked for discarding.

5 The established timing of the container draining period is preferably effected by electric apparatus connecting with an electric motor 35 which preferably is the main driving element of 10 the coating machine. The electric apparatus is also connected with a normally deenergized electric solenoid 36. The motor and the solenoid are schematically shown in the wiring diagram of Fig. 7. The solenoid is formed with a movable core 38 which is connected to the outer end of an arm 39 mounted on a pivot shaft 41 carried in a bearing 42 in the machine main frame.

The pivot shaft 41 also carries an arm 43 which is disposed adjacent the outer edge of a timing disc 44. This timing disc is carried on the outer 20 end of the coating conveyor sprocket shaft. The disc, the arm connection with the solenoid, and the solenoid itself are housed in a casing 45 (Fig. 1) which is secured to the machine main frame adjacent the sprocket shaft.

25 The timing disc 44 carries a plurality of frictionally held timing pins 51 which are spaced around the disc adjacent its outer periphery. These pins normally project from the back of the disc and move past the arm 43 as the disc revolves.

30 When the machine stops, the solenoid 36 is energized and this moves its core 38 in the direction of the arrow. Shifting of the solenoid core rocks the arm 43 against the adjacent pin 51 in the timing disc 44 and thus pushes the pin forwardly so that it projects from the front of the disc. The disc rotates in a clockwise direction as viewed in Fig. 7 and thus the projected pin is carried downwardly into engagement with 35 40 and momentarily depresses an actuating pin 54 of a movable switch contact 55. The switch contact before such movement engages with a stationary upper contact 56 of an electric switch 57. The actuating pin is slidably carried in a boss 58 on the machine frame.

45 Depression of the actuating pin 54 shifts the contact 55 of switch 57 into engagement with a stationary lower contact 61 and this deenergizes a normally energized container marking or indicating solenoid 64. This closing of the contacts 55, 61 and the deenergizing of the solenoid 64 is effected a predetermined length of time after the timing pin 51 has been pushed in so that the over-drained container in the meantime will be brought into a position where it can be operated upon to better advantage.

50 A movable core 65 of the solenoid 64 is connected with a pivot arm 66 mounted on a pivot shaft 67 carried in bearings 68 (see Fig. 1) of a bracket 69 secured to the machine frame adjacent the turret 25. The inner end of the pivot arm 66 carries an elongated shoe 71 which extends across and above the path of travel of the opened closure elements on the containers as they enter the 55 turret.

55 When the solenoid 64 is deenergized and the pivot arm 66 is rocked, the shoe 71 is moved down against the closure element of the passing over-drained container. Thus the closure element is closed down tight over the filling opening in the container and the container is thus indicated as an over-drained container. Upon inspection it is apparent at once that there is a closed container when normally such a container is open, and therefore such is discarded. If de-

sired, the container can be otherwise marked such as by imprinting a mark thereon or by mutilating the container so that inspection will readily show that the container should be discarded.

If the electric motor 35 starts and stops in rapid succession, an accumulator mechanism generally indicated by the numeral 75 (Fig. 7) is brought into play to sum up or accumulate the short idle periods preparatory to energizing the pin-setting solenoid 36 as hereinbefore explained. This accumulator mechanism includes a timing motor 76 and an auxiliary timing motor 77. The rotor shaft of the timing motor 76 carries an edge cam 78 having a high spot 79 and an edge cam 81 having a low spot 82.

The rotor shaft of the auxiliary timing motor 77 carries a clutch 85, an edge cam 86 having a high spot 87 and an edge cam 88 having a low spot 89. The shaft also carries a drum 91 having secured thereto a wire 92 which is connected to one end of a tension spring 93. The other end of the spring is secured to a block 94 on the main frame of the machine. The spring normally maintains the rotor shaft of the motor 77 in a predetermined position which is established by engagement of a pin 96 in the cam 88, with a stop 97 on the machine main frame. The clutch 85 is actuated by a pivotally mounted arm 101 which is connected to the outer end of a movable core 102 of a normally deenergized clutch solenoid 103.

Referring again to the wiring diagram in Fig. 7 it will be seen that electric energy for the operation of the various electric motors and solenoids used in the machine is transmitted preferably from a generator 105 having connected thereto a main lead wire 106 and a return lead wire 107. This electric energy is transmitted to the machine motor 35 by way of a wire 111 which connects with the main lead wire 106, a normally open switch 112, wires 113, 114, motor 35, and a wire 115 which connects with the return wire 107. When the switch 112 is closed, electric energy flows along this circuit and excites the motor 35 which in turn operates the machine.

Electric energy flowing along this motor circuit also energizes a relay solenoid 118 of a relay switch 119 having a double set of contact switches 121, 122, mounted on a movable core 123. The solenoid is connected by a wire 124 to the motor wire 113 and by a wire 125 to the generator return wire 107. Energy flowing along this relay circuit energizes the solenoid 118 and thus maintains the contact switches 121, 122 normally open.

Stopping of the machine for any reason is effected by opening the main switch 112. Whenever this switch is opened the motor circuit is broken, the motor thus stops and the machine ceases operation. Opening of the switch also breaks the relay circuit and thus deenergizes the relay solenoid 118. This closes the contact switches 121, 122.

Closing of the contact switch 121 establishes a time delay circuit which includes a time delay solenoid 127 having a movable core 128. One end of the core carries a delay contact switch 129 while the other end carries a plunger 131 of a dash pot or the like time delay device 132. The time delay solenoid 127 is connected by a wire 135 to the generator lead wire 106 and by a wire 136 and a wire 137 to one of the stationary elements of the contact switch 121. The other

stationary element of the contact switch 121 is connected by a wire 138 to the generator return wire 107.

Hence closing of the contact switch 121 completes the time delay circuit and electric energy flowing along the circuit energizes the time delay solenoid 127. Energizing of this solenoid shifts its movable core 128 to close the time delay switch 129. However, this closing of the switch 129 is not immediate because of the dash pot device 132. This dash pot device is set under certain conditions to delay the closing of the switch for ten seconds. It is this dash pot device that times the draining of the containers in the coating conveyor 13, as hereinbefore described.

If the motor switch 112 closes and restarts the motor and the machine before the ten second period has elapsed, the relay solenoid 118 is energized again and the contact switch 121 is opened. This breaks the time delay circuit and the delay solenoid 127 thereupon is deenergized. The plunger 131 of the dash pot 132 thus returns to its original position in the pot before the delay switch 129 closes and thus it is ready for a subsequent operation. Such a lapsing of the ten second time period is in effect an indication that the containers have not been over drained and that they are suitable for commercial use.

However, if the machine remains stopped long enough to permit the dash pot 132 to operate for its total ten second period, the delay switch 129 closes at the end of the period and thus a new circuit that includes the pin-setting solenoid 36, is established. Closing of the delay switch 129 permits electric energy to flow along a wire 141 which connects with the generator return wire 107, through the closed time delay switch 129, along a connecting wire 142 and a wire 143, through the pin-setting solenoid 36, and thence by a wire 144 back to the generator lead wire 106. The solenoid is thus energized and its core 38 is actuated to rock the arms 39, 43 and thus set the adjacent pin 51 in the disc 44, as hereinbefore explained.

As hereinbefore mentioned, the pin-set solenoid 36 is also energized to set one or more pins 51 in the disc 44 when the machine starts and stops in such rapid succession that it is idle for ten seconds in any period of thirty seconds. It will be remembered that this is brought about by the accumulator device 75 which is set in motion by the closing of the contact switches 121, 122 when the machine motor 35 stops. An explanation of the operation of this accumulator device 75 and its cooperating circuits will now be given.

When the contact switch 122 closes by the energization of the relay switch 119, a circuit is established which includes the timing motor 76 and the clutch solenoid 103. This circuit comprises a wire 151 which connects with the generator return wire 107, the closed contact switch 122, a wire 152 which is connected to a movable contact 153 of a normally open cam switch 154. The movable contact normally engages in the low spot 82 in the periphery of the edge cam 81. The contact is connected by a wire 156 to one side of an armature 157 of the timing motor 76. The other side of the armature is connected by a wire 158 to the generator lead wire 106.

Electric energy flowing along this circuit excites the timing motor 76 and thus sets it in operation. This starts the cams 78, 81 rotating. As soon as the cam 81 begins rotating, the mov-

able contact 153 of cam switch 154 rides out of the low spot 82 in the cam and thus closes the switch by bringing the movable contact against a stationary contact 181.

Closing of the cam switch 154 establishes a holding circuit for the timing motor 76 and this holding circuit maintains the motor circuit and clutch circuit in operation for a period of thirty seconds, the length of time required for a complete rotation of the cam 81, even though the machine again starts up and thus opens the contact switch 122. This holding circuit cuts out the contact switch 122 and transmits electric energy direct from the generator return wire 107 to the timing motor 76 by way of a wire 163, through the closed contacts 161, 153 of the cam switch 154, and thus along the connecting wire 156 to the timing motor 76.

The clutch circuit is established simultaneously with the timing motor circuit. Electric energy for this circuit flows from the generator return wire 107 along wire 151, closed contact switch 122, wire 152 to the movable contact 153 of the cam switch 154, and then follows a connecting wire 165 to the clutch solenoid 103, through the solenoid and thence along a wire 166 to the generator lead wire 106. Energy flowing along this circuit energizes the clutch solenoid 103 and thus draws its core 102 inwardly.

This rocks the clutch lever 101 and engages the friction plates of the clutch 85 on the rotor shaft of the auxiliary timing motor 77. This motor is not operating at this time. However, the clutch solenoid when once energized is maintained in this condition by the holding circuit of the timing motor 76 for a period of thirty seconds, the time required for one complete rotation of the cam 81.

If the machine stops and restarts one or more times during this period of thirty seconds, the auxiliary timing motor 77 starts up each time the machine stops and the motor continues operating for as long as the machine is idle. Starting of the auxiliary timing motor is effected by the closing of the normally open contact switch 121 which it will be remembered closes every time the machine stops operating.

When this contact switch 121 closes, electric energy is transmitted from the generator return wire 107, along wire 138, closed contact switch 121, wire 137 to a stationary contact 171 of a normally closed cam switch 172 having a movable contact 173 which rides on the periphery of the edge cam 88 on the rotor shaft of the auxiliary timing motor 77. The current passes through this closed cam switch 172, and flows along a wire 174, through an armature 175 of the auxiliary timing motor 77, and thence passes along wire 158 to the generator lead wire 106. Energy flowing along this circuit excites the auxiliary timing motor to rotation and thus through the closed clutch 85, rotates the edge cams 86, 88 and the drum 91.

The cycle of rotation of the auxiliary timing motor 77 is ten seconds and if the accumulation of the short stop and start or idle periods of the machine equals ten seconds during the thirty second time period of the timing motor, the auxiliary timing motor completes its cycle and thus establishes the pin-setting solenoid circuit to energize the pin-setting solenoid 36 and thus set one or more of the pins 51 in the timing disc 44 to designate the containers which were overdrained during the frequent stopping and re-starting of the machine.

Each time the auxiliary timing motor 77 rotates, it revolves the edge cams 86, 88 through a portion of a rotation. When the motor stops, the cams remain in their advanced position until the next time the motor starts and then they are further rotated. Each time the cams 86, 88 are rotated the drum 91 is also rotated and thus winds the wire 92 a little further around the drum against the resistance of the spring 93. When the cam 88 has revolved far enough to complete its cycle of ten seconds, its high spot 87 engages a movable contact 181 of a normally open cam switch 182 and thus closes this switch. At the same time the movable contact 173 of cam switch 172 falls into the low spot 89 of edge cam 88 and thus opens the switch 172. This breaks the auxiliary timing motor circuit and thus stops operation of the auxiliary timing motor 77.

A stationary contact 183 of the cam switch 182 connects with the wire 143 which leads to the pin-setting solenoid 36. The movable contact 181 of the cam switch is connected by a wire 185 to a movable contact 186 which rides on the periphery of the timing motor edge cam 78. This movable contact is part of a normally open cam switch 187 having a stationary contact 188 which is connected by a wire 189 to the wire 163.

Hence just before the timing motor 76 completes its cycle period of thirty seconds, the high spot 79 of the edge cam 78 closes the cam switch 187 and if at the same time the cam switch 182 of the auxiliary timing motor 77 is closed, a circuit is completed to the pin-setting solenoid. Electric energy then flows from the generator return wire 107, along wires 163, 189, closed cam switch 187, wire 185, closed cam switch 182, and thence along wire 143 to the pin-setting solenoid.

When the timing motor 76 completes its cycle of thirty seconds and the movable element 186 of cam switch 187 rides off the high spot 79 on cam 78, the low spot 82 of cam 81 comes adjacent the movable contact 153 of the cam switch 154 and thereby opens the latter switch. This breaks the timing motor holding circuit and hence the timing motor stops rotating and remains ready for the start of a new cycle.

Breaking of the timing motor holding circuit also breaks the clutch solenoid circuit and this deenergizes the clutch solenoid 103. De-energizing of the clutch solenoid rocks the clutch lever 101 away from the clutch 85 and thereby releases the cams 86, 88 from the auxiliary timing motor 77. The tension spring 93 thereupon pulls on the wire 92 around the drum 91 and thus reversely rotates the cams into their original position. The pin 96 in cam 88 strikes against the stop 97 when the cams are fully returned and thus holds them ready for a new cycle. This completes the operation of the accumulating mechanism 75.

As hereinbefore mentioned when a container is over-drained and a pin 51 in the rotating disc 44 is "set," the pin through suitable electric circuits, de-energizes the marking or indicating device solenoid 64 when the container arrives adjacent the marking or indicating device and this closes the closure element B on the container. Normally the marking device solenoid 64 is maintained in an energized condition by electric energy which flows from the generator lead wire 106, along a connecting wire 191, the solenoid 64, a wire 192, a normally closed switch 193 of a double contact relay 194, and thence by a wire 195 to the generator return wire 107.

Breaking of this marking device solenoid circuit is effected by opening of the switch 193 and

this is done by the "set" pin 51 in the rotating disc 44. The set pin 51 engages against and depresses the actuating pin 54 of switch 57. The movable contact 55 of the switch is pressed down against the stationary contact 56 and this establishes a circuit which includes the double contact relay 194.

Electric energy flows along this new circuit by way of a wire 201 which connects with the generator return wire 107, the closed switch contacts 55, 56, a wire 202, a normally closed contact switch 203, a wire 204, a solenoid 205 of the relay 194, and thence by way of a wire 207 back to the generator lead wire 106. The energy flowing along this circuit energizes the relay solenoid 205 and thus opens the contact switch 193.

Simultaneously with the opening of the contact switch 193, a second normally open contact switch 209 of the relay 194 is closed to establish a holding circuit to maintain the marking device solenoid 64 in a de-energized condition for a predetermined period of time. With the contact switch 209 closed, energy flows from the generator lead wire 106, along the wire 207, relay solenoid 205, wire 204, closed contact switch 203, a connecting wire 211, closed switch 209, and wire 212 back to the generator return wire 107.

Usually when the machine stops longer than a ten second period more than one container will be over-drained and hence all of those which are over-drained must be indicated for discard. It is for this reason that the holding circuit just described is provided. The duration of the holding circuit period is preferably the length of time it takes the disc 44 to make one half a revolution. Thus one half a revolution after a "set" pin 51 closes the switch contacts 55, 56 of switch 57, the pin comes into engagement with an auxiliary actuating pin 215 which connects with the movable contact of the switch 203.

The auxiliary actuating pin 215 is disposed in a boss 216 formed on the machine frame. Engagement of this pin opens the switch 203 and thereby breaks the holding circuit. This de-energizes the relay solenoid 205 of relay 194 and thus opens switch 209 and closes switch 193. Closing of switch 193 reestablishes the marking device solenoid circuit and thus the solenoid 64 is reenergized. The shoe 71 thereupon rises out of the path of travel of the container closure elements and the containers continue on through the machine with its closure elements in normally open position.

After engaging the auxiliary actuating pin pin 215 of switch 203, the "set" pin 51 continues on with the rotation of the disc 44 and comes into engagement with a tapered "reset" cam block 218. This cam block is stationary and is secured to a boss 219 on the machine main frame. As the pin 51 passes this cam block it rides against the tapered surface on the cam and is thereby pushed back into its original position. This completes the cycle of a pin 51.

Under normal operating conditions only one pin 51 will be "set" or pushed out for each ten second period of machine stoppage. However, under certain conditions where the machine stops and starts in rapid succession more than one pin 51 may be "set." It is then necessary to push all but the last "set" pin back into its original position immediately after they have engaged the actuating pin 54, otherwise the switch 203 will be opened by the first "set" pin instead of the last and the relay switch 194 will not main-

tain the holding circuit long enough to insure closing of the closure elements on all the containers which have been over-drained.

The early "resetting" of the pins 51 is brought about by a curved wing 22 which is located adjacent the disc 44 in spaced relation thereto and extends along the path of travel of the pins 51 as they move from the actuating pin 54 to the auxiliary actuating pin 215. This wing 222 is formed on an arm 233 which is mounted on a vertical shaft 224 carried in a bearing 225 of the machine frame. The shaft also carries a lever 226 which at its outer end is pivotally connected to a movable core 227 of a normally energized "reset" solenoid 228. The "reset" solenoid is connected by a wire 231 to the generator lead wire 106, and by a wire 232 to the stationary contact 56 of the switch 57.

Under normal operation of the machine the movable contact 55 of switch 57 is in engagement with the stationary contact 56. Electric energy then flows from the generator lead wire 106, along wire 231, "reset" solenoid 228, wire 232, contacts 56, 55, and wire 201 to the generator return wire 107. This energy maintains the solenoid in an energized condition.

However, every time the actuating pin 54 is engaged by a pin 51, the movable contact 55 is momentarily shifted away from the contact 56 and this breaks the "reset" circuit. The solenoid 228 becomes de-energized and this permits an enclosed spring in the solenoid casing to shift the core 227 and the arms 226, 233 and thus swing the wing 222 inwardly against the disc 44. Any "set" pins 51 that are in the path of the wing are thus pushed back into their original position where they will not engage the auxiliary actuating pin 215.

Since the breaking of the solenoid circuit is only momentary the solenoid is immediately re-energized and the wing 222 is thus shifted away from the disc 44. Thus it will be only the last "set" pin 51 which will remain "set" and this pin will by-pass or clear the wing 222 and thus control the duration of the holding circuit period.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

We claim:

1. In a machine for coating containers, including means for applying liquid coating material onto a container, the combination of a runway for receiving and supporting coated containers so that excess coating material will drain off, a conveyor for propelling the draining containers along said runway at a predetermined speed so that they will be drained a predetermined amount upon traversing a predetermined length of said runway, means for moving said conveyor, means controlled by said conveyor moving means and operable when said conveyor temporarily stops for timing the total of idle periods of the conveyor to determine when the sum of such idle periods equals a predetermined period of time in excess of which a container traversing the runway is overdrained, and means operable by said timing means when the predetermined period of time is thus totaled for operating upon over-

drained containers to designate such containers as over-drained, so that they may be readily detected upon visual inspection and discarded.

2. In a machine for coating containers, wherein means are provided for applying liquid coating material onto a container, the combination of a conveyor for propelling the coated containers along a predetermined path of travel to allow them to drain for a predetermined period of time so that the resulting film of coating material remaining on the container will be of a predetermined thickness, an electric motor for driving said conveyor, electrical means operable when said motor temporarily stops for determining when the idle period of said motor exceeds the draining period of the containers being propelled by the conveyor, means for engaging over-drained containers to alter their physical appearance so that they may be readily detected, and electro-mechanical means operable by said electrical means for actuating said container engaging means.

3. In a machine for coating containers, wherein means are provided for applying liquid coating material onto a container, the combination of a conveyor for propelling the coated containers along a predetermined path of travel to allow them to drain for a predetermined period of time so that the resulting film of coating material remaining on the container will be of a predetermined thickness, an electric motor for driving said conveyor, electrical timing means operable when said motor temporarily stops and continuing in operation for a predetermined period of time even though said motor again starts for spacing off a limited draining cycle in excess of which the containers being propelled by the conveyor are over-drained, electrical accumulator means operable when said draining cycle begins and concurrently operable when the motor stops and starts for timing the total of idle periods of the motor, electro-mechanical means operable by said accumulator means when the total idle periods of the motor exceed a predetermined amount during one draining cycle, and means operable by said electro-mechanical means for engaging and altering the appearance of over-drained containers so that they may be readily detected upon inspection and discarded.

4. In a machine for coating containers, wherein means are provided for applying liquid coating material onto a container, the combination of a conveyor for propelling the coated containers along a predetermined path of travel to allow them to drain for a predetermined period of time so that the resulting film of coating material remaining on the container will be of a predetermined thickness, an electric motor for driving said conveyor, electrical means operable when said motor temporarily stops for determining when the idle period of said motor exceeds the draining period of the containers being propelled by the conveyor, electrical accumulator means operable when said motor stops and starts in rapid succession for timing the total of idle periods of the motor to determine when a container is over-drained, an electric solenoid operable by said electrical means and by said accumulator means, means responsive to the operation of said solenoid for engaging and altering the physical appearance of overdrained containers so that they may be readily detected for discarding, a rotatable time delay disc, a plurality of push pins in said disc for actuating said container engaging means when the over-drained containers are moved ad-

jacent thereto, and means for setting said push pins to actuate said container engaging means.

5. In a machine for coating containers, said machine including means for applying liquid coating material onto a container and means for draining the coated container for a predetermined period of time, the combination of electrical means associated with said draining means for determining when a container is over-drained, and means actuated by said electrical means for operating on over-drained containers so that they may be readily detected and discarded.

15 6. In a machine for coating containers, including means for applying liquid coating material onto a container, the combination of a runway for receiving and supporting coated containers so that excess coating material will drain off, a conveyor for propelling the draining containers along said runway at a predetermined speed so that they will be drained a predetermined amount upon traversing a predetermined length of said runway, timing means operable when said conveyor temporarily stops for determining when a container remains on said runway in excess of a predetermined period of time, and means actuated by said timing means for operating upon containers which have been over-drained to designate the containers as such, so that the over-drained containers may be readily detected by visual inspection.

30 7. In a machine for coating containers wherein means are provided for applying liquid coating material onto a container, the combination of a runway for receiving and supporting coated containers so that excess coating material will drain off, a conveyor for propelling the draining containers along said runway at a predetermined speed so that they will be drained a predetermined amount upon traversing a predetermined length of said runway, timing means operable when said conveyor temporarily stops for determining when a container remains on said runway in excess of a predetermined period of time so as to become overdrained, means operable by said timing means for engaging and designating overdrained containers as such, so that they may be readily detected, and means for delaying the actuation of said container engaging means until the overdrained containers to be engaged and designated as such are moved adjacent said engaging means.

45 8. In a machine for coating containers wherein means are provided for applying liquid coating material onto a container, the combination of a runway for receiving and supporting coated containers so that excess coating material will drain off, a conveyor for propelling the draining containers along said runway at a predetermined speed so that they will be drained a predetermined amount upon traversing a predetermined length of said runway, timing means operable when said conveyor temporarily stops for determining when a container remains on said runway in excess of a predetermined period of time so as to become overdrained, means operable by said timing means for engaging and operating upon such overdrained containers so that they may be readily detected upon visual inspection as such and thus discarded, and means for holding said container engaging means in container engaging position until all of the overdrained containers are operated upon and thus designated as overdrained.
